DESIGN FOR A TEXTILE FABRIC

Carl Lang, New York, N. Y.

Application January 25, 1937, Serial No. 67,284

Term of patent 3½ years

To all whom it may concern:

Be it known that I, Carl Lang, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure in the drawing is a plan view of a textile fabric showing my new design. The design unit is contained between the dot and dash lines, which unit is repeated in regular succession, as indicated by the extensions beyond the unit boundaries.

I claim:

The ornamental design for a textile fabric substantially as shown and described.

CARL LANG.
